UNITED STATES PATENT OFFICE.

ARTHUR ERNEST JERRAM, OF LEICESTER, ENGLAND, ASSIGNOR TO UNITED SHOE MACHINERY COMPANY, OF PATERSON, NEW JERSEY, A CORPORATION OF NEW JERSEY.

LASTING-MACHINE.

1,022,420.

Specification of Letters Patent.

Patented Apr. 9, 1912.

Application filed September 26, 1904. Serial No. 225,963.

To all whom it may concern:

Be it known that I, ARTHUR E. JERRAM, a subject of the King of England, residing at Leicester, in the county of Leicester, England, have invented certain Improvements in Lasting-Machines, of which the following description, in connection with the accompanying drawings, is a specification, like reference characters on the drawings indicating like parts in the several figures.

This invention relates to lasting machines and has for its object to improve the construction and operation of certain portions of the machine.

A very important feature of the invention consists in an improved shoe support or jack for holding a shoe while it is being lasted or otherwise operated upon. The jack herein shown as embodying this feature of my invention comprises two carriages mounted on a suitable base, which is adapted to be raised and lowered as usual for presenting the shoe carried by the jack to the lasting mechanisms. One of the carriages is provided with a heel pin for engaging the usual pin hole of the last, while the other carriage is provided with arms upon which is supported a wiper or band for engaging and embracing the toe portion of a shoe upon the last. This wiper or band has the usual function of end embracing bands in that it engages and clamps the upper materials about the end portion of the last and holds them in position to be laid over the last bottom by the lasting or crimping jaws. In addition to this function the band has, as herein shown, the function of wiping the upper upwardly about the toe portion of the last. It is therefore known in the art both as a wiper and a band and both names are herein employed without implying any other limitation than the context requires. Operating means is provided for actuating the wiper to cause it to move up along the upper portion of the last for pressing or wiping the upper toward and over the toe of the last and holding it in position to be engaged by the crimping jaws of the lasting mechanism. The supporting arms for the wiper or band are herein shown as levers mounted on fulcra in guides on the carriage, the levers being free to rock in all directions and

also to slide longitudinally in the guides. It is to be understood, however, that many of the advantages of the invention may be obtained without employing levers as the supporting arms for the wipers. In the present embodiment of the invention means is provided for adjusting the supporting arms to position their upper ends different distances apart and thereby adapt the band or wiper carried by the arms for shoes of widely different widths. I have provided also a novel connection between the supporting arms and the band or wiper, whereby the band may spread or contract to conform to shoes varying slightly in width without the necessity of adjusting the supporting arms. The supporting arms are arranged to yield together in the same direction transversely of the jack to equalize the shoe embracing pressure at the ends of the band in the event that the last is unsymmetrically shaped at the toe. A further movement of the arms and band together is permitted if required to center an unsymmetrical shoe toe relatively to the crimping jaws, if as herein shown, the jaws or the jack head or both have predetermined lateral positions in the machine. With such an arrangement as this the crimping jaws of the lasting mechanism exert greater pressure sometimes upon one than upon the other side of a shoe being lasted. As herein shown, the lower ends of the arms are connected to a common support which is slidably mounted in the carriage so that the arms may move in company transversely of the jack. Improved means is also provided for supporting the arms so that they may yield to permit the wiper to move longitudinally of the jack while being moved upwardly into position about the toe of the shoe in case the jack is not properly adjusted for the length of the shoe thereon. The machine is also equipped with novel means for angularly adjusting the wiper transversely of the jack to adapt the position of that lasting means laterally to the transverse inclination of the portion of the last with which it cooperates. This adjustment which is made about an axis extending lengthwise of the shoe enables the wiper to be so positioned that its upper edge will be in a plane parallel with the last bot-

tom when the wiper has been raised up to the last edge in wiping the upper into last-
5 ed position about the end faces of the last ready for the crimping jaws to fold it in-
wardly over the last bottom. It is advan-
10 tageous for the wiper to occupy a raised position which is flush and parallel with the last bottom, whatever may be the inclination of the bottom of the particular last in the machine, in order that the lasting means may coöperate with the crimping jaws in forming a square, well-defined edge on the shoe at the edge of the last. The crimping jaws are also arranged for angular move-
15 ment that they may be positioned in a plane parallel with the plane of the last bottom.

As mechanisms of this class have heretofore been constructed the toe wiper and the means for actuating it into position for em-
20 bracing the toe of the shoe have been so ar-
ranged that the upper edge of the wiper, as it swung upwardly about its pivotal connec-
25 tion with the supporting arms, exerted on the shoe a wiping action in a direction re-
verse of that in which it is desired that the wiping action shall occur. This takes place particularly during the latter portion of the upward swing of the wiper and causes the portion of wiper acting on the side of the
30 shoe to rub the upper toward the heel instead of toward the toe, as is desired. In the machine of the present invention this difficulty is obviated by imparting to the wiper a sup-
plemental movement longitudinal of the
35 jack and in a direction away from the heel of the last. As herein shown, this supplemental movement is imparted by means ad-
ditional to the means which imparts to the wiper its main movement about its pivotal
40 connection with the supporting arms. The two means together cause the wiper to travel during its entire movement into operative
45 position in a direction toward the toe of the last, whereby all the portions of the upper engaged by the wiper are strained in the de-
sired direction. In the illustrated embodiment of this feature of the invention the crank shaft which, through the usual crank arm and link, is employed for swinging the
50 wiper upwardly and forwardly about its pivots is provided with an eccentric which is operatively connected with the wiper sup-
porting arms by means which imparts to the supporting arms and wiper a movement to-
55 ward the toe of the last while the wiper is being swung upwardly. This supplemental movement in addition to the swinging main movement of the wiper results in such an over-compensation for the rearward move-
60 ment which the upper edge of the wiper would otherwise get that the upper will be wiped toward the toe of the last at all points engaged by the wiper.

Another feature of the invention consists
65 in combining with the usual mechanism for

raising and lowering the shoe support or jack a means for automatically locking the heel and toe lasting mechanisms in desired position when the jack is raised and for un-
locking said lasting mechanisms when the jack is lowered. Preferably this arrange-
70 ment is such that the lasting mechanisms are securely locked with the desired one in operative position before the jack in rising reaches the level of said lasting mechanism,
75 whereby all danger is avoided of the lasting mechanisms being in such improper position as to be accidentally engaged by the shoe when the jack is raised.

Other features of the invention, including
80 certain details of construction and combina-
tions of parts, will be hereinafter pointed
out and described in the claims.

Figure 1 is a side elevation of a lasting
machine embodying this invention. Fig. 2
85 is an end elevation on an enlarged scale of
the forepart of the shoe support or jack, in-
cluding the toe band or wiper with its car-
riage and a preferred form of supporting
and adjusting mechanism. Fig. 3 is a side
90 elevation of the construction shown in Fig.
2. Fig. 4 is a detail view showing in side
elevation a cap plate to be described and the
parts immediately behind the cap plate.
Fig. 5 is a view showing a modified con-
95 struction of means for angularly adjusting
the toe band or wiper transversely of the
shoe support. Fig. 6 is an end elevation of
the construction shown in Fig. 5. Figs. 6^a
and 6^b are vertical sections illustrating de-
100 tails of the construction shown in Figs. 5
and 6. Fig. 7 is a side elevation on an en-
larged scale of the toe lasting mechanism
which I prefer to employ, said mechanism
being shown also in Fig. 1. Fig. 8 is a front
105 elevation of the mechanism shown in Fig. 7.
Fig. 9 is a section on the line 9—9 of Fig. 8.
Fig. 10 is a section on the line 10—10 of
Fig. 9.

The frame of the machine comprises an
110 upright hollow column having a backwardly
extending arm 2 provided with a bearing
3 to receive the stem of the rotatable head 4
which carries the toe and heel lasting mecha-
nisms. Said frame also has a forwardly
115 extending arm 5 having a bearing 6 to re-
ceive the spindle of the shoe support or jack.
The jack comprises a head 8 from which de-
pends a spindle 10, said spindle being capa-
ble of both rotary and endwise movement
120 in the bearing 6. Mounted for sliding
movement on the head 8 of the jack is a
carriage 12 for the usual last pin and a car-
riage 14 for the toe band or wiper 16. The
jack spindle 10 is provided with two slots
125 18 and 19 arranged to be engaged by a
spring-pressed locking pin 20 for securing
the jack against accidental rotation when
the shoe supported by the jack is presented
130 with either its toe or its heel end in posi-

tion to be acted upon by the toe and heel lasting mechanisms. The upper ends of the slots 18 and 19 are beveled, as shown, so that when the jack is depressed the locking pin will be forced out of the slot engaged by it and will bear against the cylindrical portion of the spindle, which with the entire jack may then be turned to present the desired end of the shoe to the lasting mechanism. The said toe and heel lasting mechanisms are mounted upon arms 22, 24 extending from the lasting head approximately at right angles to each other. Means is provided for locking the head against rotation when either the toe or the heel lasting mechanism is in position for acting upon the shoe, and for the purpose of automatically effecting the locking and unlocking of the lasting head the locking pin 26, which is mounted in the arm 2 and arranged to engage recesses in the lower face of the head, is connected with the usual treadle employed for raising and lowering the jack. To this end a lever 28 is pivoted to the frame at 30 and its free end engages a recess 32 in the side of the locking pin. Said lever 28 is joined by a link 34 with a treadle 36 which is arranged to be depressed for lowering the jack. A spring 40 is arranged for normally pressing the locking device 26 upwardly into the recesses in the lower face of the head 4. With this arrangement the locking device will be withdrawn automatically when the treadle 36 is depressed for lowering the jack, as it will have to be in order for the shoe to be turned whenever the lasting mechanism for the other end of the shoe is to be employed, and will be automatically raised into locking engagement with the head 4 when the jack is permitted to rise under the influence of the spring 42, which has connection with the treadle and a fixed portion of the frame, as shown in Fig. 1.

It is desirable that the lasting mechanisms be securely locked in their operative positions before the jack in rising reaches an elevation at which the shoe carried thereby might engage the lasting mechanisms. For the purpose of insuring this locking of the lasting mechanisms in advance of the complete rise of the jack the link 34 is passed loosely through the treadle lever 36 and a stop 44 is provided at some distance below the treadle when the latter is in its normal position. This arrangement permits the device 26 to be elevated by its spring 40 for making locking engagement with the lasting head during the first portion of the rise of the jack and before the shoe reaches the plane in which the lasting wipers are located.

The carriages 12 and 14 for supporting the heel pin and toe wiper respectively are arranged to be moved simultaneously to- ward or from the center of the jack, and to this end the carriages are connected by a right and left-handed screw-threaded rod 50 rotatably mounted in the head of the jack and held from endwise movement therein. The rod 50 is provided with a worm gear 52 engaged by a worm 54 having on its outer end a hand wheel 56.

The carriage 12 supports a casing 60 having a tubular portion adapted to receive a carrier 62 for the usual last pin 64. The casing is pivotally connected to the carriage 12 at a point 66 located at the rear side of the carrier 62. The casing is adjusted about the pivot 66 for canting the heel pin more or less forwardly by means of a screw 68 having a handle 70 and entering a threaded opening in a block 72 rotatably mounted in the lower end of the casing, as shown in dotted lines in Fig. 1. The carrier 62 for the last pin is exteriorly screw-threaded and is engaged by a nut 74 held against longitudinal movement in a notch in the casing. A stop screw 75 engages a longitudinal groove in the carrier and holds it against rotation while permitting it to be adjusted longitudinally by rotating the nut 74.

The toe band or wiper 16 is carried on two arms 80, Fig. 2, each of which is provided intermediate its ends with a ball-shaped portion 82 received in a vertical cylindrical bearing 84 formed on the wiper carriage. The lower end of each arm has an eye or socket 86 in which a cylindrical nut 88 is rotatably mounted. The nuts are oppositely screw-threaded and are engaged by correspondingly threaded portions of an adjusting screw 90 which extends transversely of the jack and is provided with an operating hand wheel 92. By turning the adjusting screw 90 the arms, which it will be observed are levers fulcrumed in the guides or bearings 84, may be rocked in opposite directions transversely of the jack, and consequently the spread of the toe wiper supported on the upper ends of the arms may be varied to accommodate lasts of considerable difference in size. The screw may at any time be operated after the wiper or band has been raised into operative position for embracing the end portion of the shoe and in any special case the band may be thus caused to clamp the upper firmly against the sides of the last and hold it while the upper is folded over the last bottom by the crimping jaws and fastened. The screw 90 may be mounted on the wiper carriage in any convenient manner so as to be capable of rotation, but not of endwise movement. Preferably, however, and as shown in the drawings, the screw is mounted in a block 94 which is secured to or formed integral with the front end of the stud 96, which is rotatably mounted and also longitudinally movable for purposes hereinafter described, in a bearing 130

supported by or formed in the wiper carriage.

For the purpose of allowing the wiper or band to act properly upon lasts of slightly 5 different sizes without having to adjust its spread by means of the adjusting screw 90, said wiper is movably supported upon or connected to the arms 80. As herein shown, the upper end of each arm 80 is formed with 10 an eye 97 which acts as a bearing for a stud 98. One end of the stud is connected with the wiper by a ball and socket joint 100 formed in a plate 102 fixed to the wiper. The other end of the stud is provided with 15 a head 104 to limit its movement toward the last and the two studs are pressed upon by two spring arms 106 which are loosely mounted between their ends upon studs 108 projecting from the wiper supporting arms 20 80. The upper ends of the spring arms 106 may be formed with openings to engage guide pins see Fig. 2 projecting from the stud 98, while the lower ends of the spring arms are provided with openings for engaging 25 pins 112 projecting from the bearings 84 before described. These pins maintain the spring arms in proper position and the pressure to be exerted by the spring arms is adjusted by thumb nuts 114 on the studs 30 108. It will be readily understood that with this construction the toe wiper may be spread somewhat to receive a wider last than that for which the supporting arms are adjusted, notwithstanding the fact that the supporting 35 arms themselves may be unyielding. It will, therefore, be necessary to manipulate the adjusting screw 90 for changing the spread of the wiper only for lasts varying considerably in width.

40 As heretofore stated, it is desirable to permit the band or wiper supporting arms 80 to yield in company transversely of the jack in the event that the toe to be embraced is unsymmetrical or that the pressure exerted by 45 the crimping jaws of the lasting mechanism is greater upon one side of the shoe than upon the other side, and to this end the block 94 hereinbefore described as carrying the adjusting screw 90, is bored to receive 50 a sleeve 102, see Figs. 2 and 6^a said sleeve being capable of both endwise movement and rotary movement within the block 94, but being fixed by means of a screw 122 to the adjusting screw 90 which passes through 55 it. The ends of the sleeve 120 are flush with the ends of the block 94 and the sleeve is normally prevented from moving endwise in the block by a stiff U-shaped spring 124, which embraces the block and engages both ends of 60 the sleeve. This spring maintains the sleeve, the adjusting screw, the supporting arms, and the band or wiper in normal central position, but will yield to allow these parts and the toe of the shoe embraced by the band or 65 wiper to move transversely of the jack to

equalize pressure of the ends of the band against the sides of the toe or the stress exerted on the shoe by the crimping jaws during the lasting operation.

Improved means is provided for angularly 70 adjusting the band or wiper transversely of the jack to adapt it for receiving lasts which are twisted,—that is, in which the plane of the bottom of the forepart is inclined transversely to the plane of the bottom of the 75 heel part. A block 130 having an upper, plane face to rest against the block 94 is provided with a segment-shaped lower face and is arranged to rock transversely of the jack in guideways in the wiper carriage. 80 The curved lower face of the block is provided with worm teeth 132 for engaging a worm 134 on an adjusting rod 136 rotatably mounted in the carriage, but prevented from endwise movement therein, and provided with an operating handle 138. The center about which the block 130 is thus adjusted is coincident with the center,—namely, the axis of the stud 96,—about which the block 94 is movable, so that an adjustment of the 90 block 130 by means of its adjusting rod 136 will incline the block 94 transversely of the jack and through the supporting arms 80 will tip the wiper transversely.

A modified construction of means for angularly adjusting the wiper transversely of the jack is shown in Figs. 5 and 6, in which the block 94 is provided with a depending portion 131 provided with a slot 133 which receives a pin 135 carried eccentrically on the end of a stud 137 which is rotatable in a bearing in the wiper carriage, the said stud having a handle 139 by means of which it may be rotated manually. It will be understood that any adjustment of the pin 135 by 100 means of the stud and handle will turn the block 94 about the axis of the stud 96 and thereby incline the block transversely of the jack and correspondingly incline the wiper 105 16.

Provision is made for enabling the toe band or wiper to yield away from the heel pin of the jack in order to accommodate 110 without adjustment shoes differing slightly in length, and to this end the stud 96 is provided with a cap plate 140, shown detached in Fig. 4, which is secured to the stud by a screw 142 and is pressed upon by springs 144 inserted in sockets formed in the outer end of the wiper carriage, as shown in Figs. 3 and 5. The springs hold the stud 96 normally in the position shown in Figs. 1 and 5 with the cap plate spaced from the adjacent face of the carriage, but when the wiper is moved into operative position with 115 relation to a shoe the springs will yield to permit the stud 96, the block 94, and the lower ends of the wiper supporting arms, to yield toward the heel of the last and thereby cause the wiper to yield in a direction away 120 125 130

from the heel of the last in case the last is slightly longer than that for which the jack has been adjusted.

In the use of the machine, the last with a shoe thereon having been placed on the heel pin, the wiper 16 requires to be swung about its pivotal connection with the supporting arms 80 from the position shown in Fig. 1 toward the operative position shown in Fig. 3. For the purpose of thus actuating the wiper a crank shaft 150 is mounted in bearings in the upper portion of the carriage and is provided with a crank arm 152 which is connected to the wiper by an adjustable link 154, the shaft being provided with an operating handle 155. The operating handle supports a spring-pressed pawl 156 adapted to engage with ratchet teeth formed on a segment plate 158, as shown in Fig. 3. Preferably and as herein shown, provision is made for imparting to the wiper a supplemental movement longitudinal of the jack while it is being swung forwardly by the means just described, and to this end an eccentric 160 is mounted on the crank shaft 150. The eccentric is embraced by an eccentric strap 162 which is connected by an arm 164 to one end of a lever 166. The lever 166 is fulcrumed intermediate its ends at 168 on the wiper carriage and its other or lower end is connected by a ball and socket joint to a slide 170 mounted in the carriage so as to be capable of horizontal movement longitudinally of the jack. The slide 170 as herein shown supports the stud 96, heretofore referred to, together with its controlling springs 144. The eccentric is fixed on the shaft 150 in such a position with relation to the crank arm 152 that when the shaft is oscillated to cause the wiper to be swung on its pivots for exerting wiping action upon the upper, the lever 166 will be rocked to move the slide 170 and with it the block 94, the adjusting screw 90, and the lower ends of the wiper supporting arms 80 toward the heel of the last and thus move the wiper, which is pivoted to the upper ends of said supporting arms, away from the heel of the last. By this means the motion toward the heel of the last, which is given to the portions of the upper edge of the wiper as the latter is swung upwardly, is counteracted and all portions of the upper edge of the wiper are caused to move forwardly or toward the toe end of the last as they move upwardly toward the last bottom. Preferably the eccentric arm 164 is connected adjustably to the lever 166 to enable the operator to regulate the amount of movement given to the lever by the eccentric and thereby vary the amount of the supplemental forward movement imparted to the wiper by the mechanism above described. To this end the arm 164 is forked to embrace the lever 166 and is piv-

otally connected to the ends of a pin 172 which extends through slots 174 in opposite sides of the lever 166, as shown most clearly in Fig. 3. The pin 172 is carried by a screw-threaded stud 176, which is adjustable longitudinally in a guideway in the lever and is engaged by a screw-threaded nut 178 carried in a notch in the lever 166 so as to be incapable of endwise movement. Rotation of the nut moves the stud 176 endwise in the lever, thereby varying the distance between the fulcrum 168 of the lever and its point of connection with the eccentric arm 164. By this means the extent of movement imparted by the eccentric 160 to the slide 170 and thence to the wiper may be varied according to the requirement of the work.

The toe and heel lasting mechanisms and their carriages are identical in construction and arrangement and only one,—namely, the toe lasting mechanism shown in side elevation in Fig. 1 and in detail in Figs. 7, 8, 9, and 10,—will be particularly described. The carriage 180 of the toe lasting mechanism is adjustable on the arm 22 toward and from the jack by means of a screw 182 mounted for rotary movement only in the carriage and entering a screw-threaded aperture in the head 4. The screw 182 is provided with a beveled pinion 184 engaged by a similar pinion on the end of a shaft 186, which is provided with a hand wheel 188 by means of which the screw may be rotated for sliding the carriage forwardly or backwardly. The carriage is formed on its front face to receive the segmental slide 190, which is connected to the carriage by an arc-shaped tongue-and-groove connection, as indicated in Figs. 1 and 7, the center about which the arc is struck being a point at or near the operating portions of the crimping jaws hereinafter described, in order that when the slide 190 is moved upon the carriage to vary the inclination of the crimping jaws the vertical position of the operative portion of the jaws may not be altered materially. The slide 190 may be adjusted upon the carriage 180 by means substantially like those above described for adjusting the carriage on the arm 22. This means comprises a hand wheel 192 Fig. 8 fixed on one end of a sleeve 194, on the other end of which is a beveled gear 196. The sleeve surrounds one end of a short rod 198, the other end of which is carried in a boss on the carriage 180. Placed approximately centrally on the rod 198 is a collar 200, and carried in a hole bored through the collar and rod is one end of a pin 202 having a beveled gear 204 fixed on it so as to engage with the beveled gear 196, the pin being rotatable in the said hole, but prevented from endwise movement, all as clearly shown in Fig. 7. The

pin 202 extends beyond the beveled gear and comprises a screw-threaded portion which engages a threaded hole in a cylindrical block 206, which is rotatably carried in a holder 208 in the slide 190. By this arrangement 5 the hand wheel 192 for operating the adjusting means for the segment slide is placed adjacent to the hand wheel 188 for the carriage adjusting means, whereby one 10 wheel after the other may be conveniently engaged by the operator. The segmental slide 190 is formed at its upper end with a bearing 210 to receive a cylindrical slide 212 which carries the crimping jaws or lasting 15 devices, said slide being movable endwise in the bearing and also adjustable angularly therein. The slide is operated by means of a lever 214 which extends through a recess running transversely across the slide 20 and said lever is pivoted to the slide by a pin 216, all as shown most clearly in Figs. 9 and 10. The inner end of the lever is rounded and projects beyond the slide into a bearing formed by a circumferential slot 218 in the wall of the bearing 210. Conveniently and as shown in Fig. 9, this bearing for the inner end of the lever may be formed in a cap or cover 220 secured to the outer side of the bearing 210 and projecting 25 within the slot 218. The handle end of the lever 214 extends beyond the slide through a longitudinal slot 222 in the bearing 210, the slot being of greater width as well as greater length than the transverse dimensions of the 30 lever, whereby the lever is allowed to have movement both horizontally and vertically for moving the cylindrical slide and the lasting plates or crimping jaws carried thereby forwardly with relation to the jack 35 and also angularly. This provision for moving the jaws angularly enables the operator to position the jaws accurately so that they shall act uniformly upon the two sides of the last, even though the plane of the bottom 40 of the last be inclined transversely. The lever 214 is connected to the crimping jaws 224, 225 by links 226, 227 respectively, the points of connection between the links and the lever being at a greater distance from 45 the inner end or fulcrum of the lever than is the pivot pin 216 which connects the lever to the slide, as is clearly shown in Fig. 9. The crimping jaws 224, 225 may be formed as shown in the drawings of two plates 50 secured together by bolts 228, and said jaws are pivoted on a hollow stud 230, see Fig. 7, said stud being mounted in a lug 232 extending forwardly from the slide 190. The portion of the stud on which the jaws are 55 pivoted is cone-shaped, as shown in Fig. 7, and a nut 234 is applied to the upper end of the hollow stud for securing it in position. 60

The toe and heel lasting mechanisms are 65 provided in accordance with this invention

with a central crimping plate 236, which is placed in the angle between the crimping jaws in position to act upon the extreme toe or heel end of the shoe for wiping the upper over the last at these points before the 70 crimping jaws close to wipe the upper inwardly on the sides. It is frequently desirable in operating on shoes of different sizes or shapes to substitute one of these central crimping plates for another of a 75 different form, and in accordance with this invention I have provided improved means for attaching the central crimping plate in position, said attaching means being adapted to enable said plate to be removed without 80 disturbing the crimping jaws 224, 225. As herein shown the central crimping plate 236 is clamped against the lower end of the hollow stud 230 by a headed bolt 238, which passes through an opening 240 in the plate 85 236 and thence extends upwardly through the hollow stud and is retained in position by a thumb nut 242. The opening 240 extends outwardly to the back edge of the plate 236, whereby when the nut 242 is 90 turned to loosen the clamping bolt the plate may be withdrawn and another plate substituted therefor without removing the clamping bolt from the machine or disturbing in any manner the crimping jaws 224, 225. 95

In the operation of the machine, the jack having been properly adjusted by the several mechanisms hereinabove described to adapt it for the particular work in hand, a last with a shoe thereon is applied to the 100 heel pin and the handle 155 is raised for rocking the crank shaft 150 and swinging the wiper upwardly about its pivotal connection with its supporting arms 80. As the wiper rises it spreads or contracts, as 105 may be required, to conform to the shape and width of the shoe. During the upward swinging movement of the wiper the eccentric 160 acts through the connections described for rocking the wiper supporting 110 arms 80 in the direction for moving the wiper forwardly away from the heel of the last, whereby the wiper is caused to force the upper forwardly toward the toe of the last as said wiper rises. If the shoe being 115 jacked is somewhat longer than that for which the toe and heel carriages have been adjusted, the springs 144 permit the wiper to yield forwardly in order that it may embrace such long last. The shoe having been 120 properly jacked with the shoe support in the position shown in Fig. 1, the treadle 36 will be depressed. In this movement of the treadle the locking devices 20 and 26 for the jack and the lasting head, respectively, will 125 be forced out of engagement with their co-operating recesses and then the jack may be turned to present the heel or the toe, as may be desired, toward the lasting mechanism and the lasting head may also be 130

turned to present the toe or the heel lasting plates in position to engage the shoe. The pressure on the treadle will then be reduced or discontinued and the spring 42 will raise the treadle and the jack for forcing the shoe upwardly into position against the lower sides of the lasting plates which will be suitably manipulated by the hand lever 214 to work the upper over the last bottom into position to be secured. When the treadle and jack are raised, as above described, the locking device 20 seats itself in the adjacent groove 19 of the jack post for holding the jack against angular movement during the lasting operation. Also during this upward movement of the treadle the spring 40 is permitted to raise the locking device 26 into position for locking the rotatable head which carries the end lasting mechanism so that said head is held against angular movement in its bearing 3 during the lasting operation.

Having set forth the nature of my invention and fully described a construction embodying the invention in a preferred form, I claim as new and desire to secure by Letters Patent of the United States:—

1. In a machine of the class described, the combination with a wiper and mechanism including supporting arms for actuating the wiper to work the upper about the fore part of a shoe toward the last bottom, of yielding connections between the wiper and arms, to permit the wiper to move with relation to the supporting arms for embracing lasts of different sizes.

2. In a machine of the class described, the combination with wipers and supporting arms therefor, of yielding connections between the wiper and the arms, said connections comprising studs pivotally connected to the end portions of the wiper and slidably connected to the arms, and yielding means for pressing the studs toward the wiper.

3. In a machine of the class described, the combination with a wiper and a carriage therefor, of supporting arms, bearings in the carriage through which the supporting arms are guided, connections between the upper ends of said arms and the wiper, and means for adjusting said ends of the arms toward and from each other to vary the spread of the wiper.

4. In a machine of the class described, the combination with a wiper and a carriage therefor, of two wiper supporting arms yieldingly mounted in the carriage for movement together transversely of the carriage.

5. A lasting machine having end lasting mechanism including lasting plates arranged to occupy a definite lateral position during operation and a jack similarly arranged and including an end embr-

acing band or wiper, combined with means to determine the lateral position of the jack, and means included in said jack to permit limited lateral movement of the shoe and band to center irregularly shaped shoes relatively to the wiper plates. 70

6. A lasting machine having end lasting mechanism including lasting plates arranged to occupy a definite lateral position during operation and a jack similarly arranged and including an end embracing band or wiper, combined with a laterally movable support for said band and yielding returning means therefor. 75

7. A lasting machine having end lasting mechanism including lasting plates arranged to occupy a definite lateral position during operation and a jack similarly arranged and including an end embracing band or wiper, combined with means for bodily adjusting 85 the band transversely of the jack.

8. A lasting apparatus having a continuous end embracing band or wiper supporting means for the free ends of the band, and operating means connected with both ends of the band to move said ends toward and from each other combined with yielding connections between the band and said supporting means constructed and arranged to press the band ends normally toward closed 95 position and to permit either end to move laterally of the jack and relatively to said supporting means to receive a wide or an unsymmetrically formed last.

9. A lasting apparatus having an end embracing band or wiper and supporting means for the free ends of the band, combined with yielding connections between the band and said supporting means constructed and arranged to maintain the band normally 100 closed and to permit either end to move laterally of the last and relatively to said supporting means to receive a wide or an unsymmetrically formed last, and means for adjusting the band supports transversely of 105 the last to vary the normal spread of the band ends.

10. A lasting apparatus having an end embracing band or wiper and supporting means for the free ends of the band combined with yielding connections between the band and said supporting means constructed and arranged to maintain the band normally closed and to permit either end to move laterally of the last and relatively to said supporting means to receive a wide or an unsymmetrically formed last, and a mounting for the band supporting means arranged to permit bodily movement of the band supports transversely of the last. 115 120 125

11. A lasting apparatus having an end embracing band or wiper and supporting means for the free ends of the band, combined with means for angularly adjusting the said wiper about an axis extending lon- 120

gitudinally of the last, said means including a segmental guide rib 130, a carriage 14, a correspondingly shaped transverse guideway in the carriage, and means 134, 138 operatively connected with said rib to effect and control said transverse movement.

12. In a machine of the class described, the combination with a wiper and a carriage, of two supporting arms, bearings in 10 the carriage through which the wiper supporting arms are guided, an adjusting screw common to both arms for rocking the arms toward and from each other, said screw being arranged to rotate and have endwise 15 movement in the carriage, and yielding means for engaging said adjusting screw to hold the screw and the arms and wiper controlled by it in a normal central position.

13. In a machine of the class described, 20 the combination with a carriage and a toe wiper, of two wiper supporting arms, a support common to said arms, a bearing on the carriage for said support, and means for holding the support in normal position in 25 said bearing, said holding means being adapted to yield to pressure and allow of movement of the support transversely of the carriage.

14. In a lasting mechanism having a toe 30 wiper and a wiper carriage, the combination with wiper supporting arms, of means for rigidly connecting said arms, and means for permitting the arms to yield in company transversely of the carriage, substantially as described.

15. In a machine of the class described, 35 the arms 80, the connecting screw having the right and left threaded portions engaging the arms for effecting simultaneous adjustment thereof, the support in which the screw is rotatable and endwise movable, the abutments formed by the sleeve 120, and yielding means for engaging the abutments to maintain the parts in normal relation but 45 permit the arms to move in company when said yielding means is overcome.

16. In a machine of the class described, the combination with a wiper and a carriage therefor, of wiper supporting arms 50 yieldingly mounted in the carriage and arranged to move together longitudinally of the carriage.

17. In a machine of the class described, 55 the combination with a wiper, a carriage therefor, and rigid wiper supporting arms mounted in the carrier by a sliding connection, of means for actuating the wiper to do its work, and yielding means comprising in 60 the sliding connection between said arms and the carriage to enable the wiper to act without adjustment upon shoes of slightly different lengths.

18. In a lasting machine, the combination with an end embracing band and its car-

riage, of two band supporting arms mounted on the carriage so as to move in company transversely of the same for the purpose described, and a yielding connection between the band and each arm to permit either side of the band to yield independently in a direction transversely of the carriage.

19. In a lasting machine, the combination with an end embracing band and its carriage, of two band supporting arms yieldingly mounted on the carriage so as to yield in company transversely and also longitudinally of the same for the purpose described.

20. In a lasting machine, the combination with an end embracing band and its carriage, of two band supporting arms fulcrumed in the carriage, and means connecting said arms at their ends remote from the band and arranged for operation to force the 85 two ends of the band simultaneously toward the shoe to clasp the upper firmly against the last.

21. In a lasting machine, the combination with an end embracing band and its carriage, of two band supporting arms fulcrumed in the carriage, and means connecting said arms at their ends remote from the band and arranged for operation to force the 90 two ends of the band simultaneously toward the shoe to clasp the upper firmly against the last, said operating means and remote ends of the arms being arranged for movement in company transversely of the shoe to equalize the pressure at the two 95 sides of the shoe.

22. In a lasting apparatus, the combination with the wiper 16 and its end support 80, of the sliding connection 97, 98 to permit spreading of the wiper, and the spring to 105 hold the wiper in a normal position, substantially as described.

23. In a machine of the class described, the combination with a carriage, a wiper, and two wiper supporting arms, of guides 110 formed in the carriage through which the arms extend, a support common to said arms and arranged for movement in a bearing in the carriage in a direction longitudinal of the carriage, and yielding means for 115 holding the support in normal position in its bearings.

24. In a machine of the class described, the combination with a carriage, a wiper, and rigid wiper supporting arms, of a support 120 which is common to both arms, and is mounted in the carriage for movement both transversely and longitudinally of the carriage.

25. In a machine of the class described, 125 the combination with a wiper, two wiper supporting arms, and a carriage provided with guides through which the wiper sup-

porting arms extend, of a block forming a support common to both wiper supporting arms and arranged for angular oscillation transverse of the carriage, and means under 5 the control of the operator for angularly adjusting the block, substantially as described.

26. A lasting machine comprising, in combination, lasting means comprising a 10 band shaped to embrace an end portion of a shoe, and a supporting mechanism therefor including a block having a segmental lower bearing face, a carriage for said block having a correspondingly curved seat for 15 the block, and means for angularly adjusting the block in said seat about an axis extending longitudinally of the last.

27. A lasting machine comprising, in combination, lasting means comprising a band 20 shaped to embrace an end portion of a shoe, and a supporting mechanism therefor including a block having a lower bearing face curved in an arc of a circle the axis of which extends lengthwise of the last, and a 25 carriage having a correspondingly curved seat for the block to permit angular adjustment of the lasting means transversely of the shoe.

28. A lasting machine having, in combination, lasting means comprising a band 30 shaped to embrace an end portion of a shoe, and a supporting mechanism therefor including a block having a lower bearing face curved in an arc of a circle the axis of which 35 extends lengthwise of the last, and a carriage having a correspondingly curved seat for the block, and connections between the block and the lasting means for effecting angular adjustment of said lasting means 40 about said axis.

29. A lasting machine comprising, in combination, lasting means 16, a supporting mechanism therefor including a block 130 having a lower bearing face curved in an 45 arc of a circle the axis 96 of which extends lengthwise of the last, and a carriage 14 having a correspondingly curved seat for the block, and connections comprising the rod 90 and the arms 80 between the block 50 130 and the lasting means for transmitting movement from the block to the said lasting means, said connections being arranged for angularly adjusting the lasting means 16 transversely of the shoe to adapt it for lasts 55 in which the plane of the shoe bottom is transversely inclined.

30. An apparatus of the class described having, in combination, means for supporting a shoe in position to be lasted, lasting 60 means comprising an end embracing band, a carriage therefor, a support, means arranged to permit tipping of the lasting means about an axis extending transversely of the last, and an arc-shaped bearing por-

tion and a correspondingly curved guideway 65 formed on the carriage and the support and arranged to permit the lasting means to move laterally to adjust said means in accordance with different transverse inclinations of last bottoms. 70

31. An apparatus of the class described having, in combination, lasting means, a support upon which the lasting means is sustained, a base upon which the support is carried for lateral rocking movement, a 75 transverse arc-shaped guideway not more than 180° in extent formed in the base and located entirely below the lasting means, a transverse curved guiding device on the support and movable in the arc-shaped 80 guideway, and means for rocking the support to position the lasting means in accordance with the transverse inclination of the last bottom.

32. In a mechanism of the class described, 85 an end lasting means comprising an end embracing band, a block arranged transversely of the last, upright arms connecting said block and said lasting means, means operatively connected with said parts for effecting adjustment of the lasting means about 90 an axis extending lengthwise of the last, and means for resisting lateral displacement of the lasting means.

33. In a mechanism of the class described, 95 an end lasting means, a carriage, a transverse block pivoted to said carriage, arms pivotally supporting the lasting means from said block, means operatively connected with the block to effect adjustment of the 100 lasting means about an axis extending lengthwise of the last, and guiding means on said carriage to resist lateral thrust of the lasting means.

34. In a mechanism of the class described, 105 an end lasting means, a carriage, a transverse block pivoted to said carriage, arms pivotally supporting the lasting means from said block, means operatively connected with the block to effect adjustment of the 110 lasting means about an axis extending lengthwise of the last, and co-operating formations on the carriage and said arms to guide and direct the movement of the arms and brace the arms against lateral thrusts 115 from the lasting means.

35. In a lasting machine, the combination with a lasting means, its carriage having bearings and two supporting arms guided in bearings in the carriage, of means for 120 angularly adjusting the lasting means transversely of the machine.

36. In a lasting machine, the combination with a lasting means, its carriage having bearings and two supporting arms guided 125 in bearings in the carriage, of a block forming a support common to both arms and mounted so as to be capable of angular os-

cillation transversely of the carriage, and means for adjusting the block angularly for the purpose described.

37. In a machine of the class described, 5 the combination with a toe wiper and means for swinging the toe wiper to wipe an upper, of means for giving the wiper during its swinging movement an additional movement longitudinally of the last and away 10 from the heel of the same.

38. In a machine of the class described, the combination with a pivoted toe wiper and supporting arms therefor, of mechanism 15 for swinging the toe wiper on its pivots to wipe an upper, and means for giving to the wiper a supplemental movement longitudinal of the last, said means comprising a slide on which the wiper supporting arms are mounted, a lever connected to said slide, 20 and an eccentric for actuating the lever, substantially as described.

39. In a machine of the class described, means for supporting the heel of a last, a pivoted toe wiper, means for swinging the 25 wiper upwardly about the toe of the last, and means for imparting to the wiper an additional movement longitudinally of the last.

40. In a machine of the class described, 30 means for supporting a last at the heel in inverted position, a toe wiper, means for moving the wiper upwardly to cause it to embrace the toe portion of the last, and means for imparting to the wiper an independent movement away from the heel of 35 the last during its upward movement.

41. In a machine of the class described, a toe wiper pivoted at its rear ends, means 40 engaging its front end to swing it about said pivots to do its work, and additional means arranged for operation therewith for bodily moving the wiper lengthwise of the last during said swinging movement.

42. In a machine of the class described, a 45 toe wiper, supports to which the wiper is pivotally connected at its free ends, means engaging its closed end to swing it about said pivotal connections to do its work, and means adjustable to impart to said pivotal 50 connections a predetermined movement lengthwise of the last during the swinging movement.

43. In a machine of the class described, a toe wiper, a support for the rear ends of 55 the wiper, a link connected to the closed end of the wiper, a fulcrum shaft, a lever mounted thereon connected to the link, a slide to which the wiper supports are connected, and connections between said shaft and said 60 slide for moving the slide as the lever is turned.

44. In a machine of the class described, the fulcrum shaft 150, the slide 170, the lever 152, 155 on the shaft and the adjustable con-

nexion 162, 164, 176, 166 from the shaft to 65 the slide for actuating the latter when the shaft is turned.

45. In an apparatus of the class described, the combination with a wiper and a carriage therefor, of two wiper supporting arms 70 crumed on the carriage and connected at their ends opposite the wiper by a cross bar arranged for movement transversely of the carriage.

46. In a machine of the class described, 75 the combination with a jack movable to place a last into or out of operative position, and a movable head carrying a plurality of lasting mechanisms, of a locking device for the head and connections between 80 the locking device and the jack whereby the locking device is automatically moved into and out of locking position as the jack is raised and lowered.

47. In a machine of the class described, a 85 jack, a movable head carrying a plurality of lasting mechanisms, and means for depressing the jack, of a locking device for the head and connections between the locking device and the jack depressing means 90 whereby the locking device is operated by said means.

48. In a machine of the class described, the combination with a spring-raised jack, 95 a treadle to depress the jack, and a movable head carrying a plurality of lasting mechanisms, of a spring-pressed pin for locking the head, an arm engaging said pin, and means connecting the arm with the treadle so that depression of the treadle 100 operates the arm to draw back the pin and unlock the head.

49. In a machine of the class described, the combination with a jack movable toward and from operative position, of a movable head carrying a plurality of lasting mechanisms, and means, including a single 105 manually operated member, for moving the jack into operative position and locking the head, said means being arranged for securing the head before the jack reaches its operative position.

50. In a lasting machine having a rotatable jack and a rotatable head with two lasting mechanisms to be used alternately, 115 in combination with means for depressing the jack below the plane of the lasting mechanisms to permit it and said head to be turned, and means for automatically locking the jack against turning movement while it 120 remains elevated and automatically unlocking it when it is depressed.

51. In a lasting machine having a rotatable jack and a rotatable head carrying 125 two lasting mechanisms to be used alternately, in combination with means for depressing the jack below the plane of the lasting mechanisms to permit it and said head

to be turned, and means for automatically locking the head against turning movement while the jack remains up and unlocking said head when the jack is depressed.

5 52. In a lasting machine having a rotatable jack and a rotatable head carrying two lasting mechanisms to be used alternately, in combination with means for depressing the jack below the plane of the lasting mechanisms to permit it and said head to be turned, and devices for automatically locking the jack and the lasting head against turning movement while the jack remains elevated and automatically unlocking them 10 when the jack is lowered.

53. In a lasting machine, having a rotatable jack and a rotatable head carrying two lasting mechanisms to be used alternately, in combination with means for depressing the jack below the plane of the lasting mechanisms to permit it and said head to be turned, and means operatively connected with the jack for locking and unlocking the lasting head.

25 54. In a lasting machine having a rotatable jack and a rotatable head carrying two lasting mechanisms to be used alternately, in combination with means for depressing the jack below the plane of the lasting mechanisms to permit it and said head to be turned, and means operatively connected with the jack for locking and unlocking the lasting head, said means being constructed and arranged to hold the lasting head from turning movement until the shoe is below the plane of interference by the lasting mechanisms and to lock said head from turning movement again before the shoe in the jack is returned to the plane 40 where it might be struck by the turning head.

55. In a lasting machine having a rotatable jack and a rotatable head carrying two lasting mechanisms to be used alternately, said jack and head being relatively 45 depressible into different planes for turning without interference, and automatically acting locking devices arranged to prevent turning movement when said parts are in interfering planes and to permit turning movements when the jack and head are in non-interfering planes.

56. A lasting machine having, in combination, a movable head carrying lasting 55 mechanism, a lock therefor, a jack, means for actuating the jack, and connections from the jack to the lock to operate the latter.

57. A lasting machine having, in combination, a movable head carrying lasting 60 mechanism, a movable jack, a lock for one of said parts, means for manually moving the other of said parts, and connections from said means to the lock to render the lock operative in one position of the manu-

ally moved part and inoperative in a different position thereof.

58. In a machine of the class described, the combination with a vertically movable shoe support arranged for angular movement, and means operating automatically 70 for locking and unlocking the support as it is moved vertically, of means for operating on the shoe, said means being arranged for angular movement toward and from operative position, and devices operatively connected with the shoe support for locking and unlocking said means in time relation with the locking and unlocking of the support.

59. In a machine of the class described, 80 the combination with a jack having a longitudinally grooved rotatable post, and a pawl for engaging the grooved post to restrain it from rotary movement, of means for operating upon a shoe carried by the 85 jack, a rotatable support for said means, a device for locking the support, and means for moving the jack post endwise, said machine having provision for causing the operation of the locking devices automatically 90 during the movement of the jack post.

60. In a machine of the class described, the combination with a cylindrical casing, a slide constructed and arranged for endwise reciprocation and for oscillation in the 95 casing, and a pair of crimping jaws mounted on the slide, of an operating lever extending through and pivoted in the slide and having one end in engagement with the casing, substantially as described.

61. In a machine of the class described, the combination with a cylindrical casing, a slide constructed and arranged for endwise reciprocation and for oscillation therein, and a pair of crimping jaws mounted on the 105 slide, of an operating lever passing through and pivoted in the slide, said lever having one end in engagement with the casing, and a handle on its opposite end, and connections between the lever and the crimping 110 jaws for opening and closing the jaws when the lever is moved to reciprocate the slide.

62. In a lasting machine, means for supporting a shoe, means for wiping the upper upwardly along the sides of the last into 115 lasted position about the last edge, independently operated crimping jaws for holding the upper inwardly from the last edge, and means for angularly adjusting the crimping jaws to the transverse inclination 120 of the last bottom.

63. In a lasting machine, means for supporting a shoe, means for wiping the upper upwardly along the sides of the last into 125 lasted position about the last edge, crimping jaws for folding the upper inwardly from the last edge, and means for angularly adjusting the crimping jaws to the transverse

- inclination of the last bottom, said machine having provision for also adjusting the wiper angularly to adapt it to the transverse inclination of the last bottom. 65
- 5 64. In a lasting machine, means for supporting a shoe, an end embracing band, crimping jaws, means for independently operating the jaws and band and means for angularly adjusting said band and said jaws 10 relatively about an axis that is substantially parallel with the plane of the shoe bottom. 70
65. In a lasting machine, means for supporting a shoe, an end embracing band, and crimping jaws arranged to act on the same 15 end of the shoe, and means for independently adjusting the band and the jaws angularly about axes extending lengthwise of the shoe. 80
66. In a lasting machine, means for supporting a shoe, an end embracing band and crimping jaws arranged to act on the same end of the shoe, and means for independently adjusting the band and the jaws about axes extending both lengthwise and trans- 25 versely of the shoe. 85
67. In a lasting machine, means for supporting a shoe, means for wiping the upper upwardly along the sides of the last into lasted position about the last edge, and 30 crimping jaws for folding the upper inwardly from the last edge, said machine having provision for relative lateral yielding movement of the wiper and jaws to center the wiped up shoe and the jaws. 90
- 35 68. In a lasting machine, means for supporting a shoe, means for wiping the upper upwardly along the sides of the last into lasted position about the last edge, crimping jaws for folding the upper inwardly from 40 the last edge, means for guiding the jaws in laterally predetermined paths and means for supporting the wiper which will permit it to yield laterally with the shoe to center the shoe in the crimping jaws. 95
- 45 69. In an end lasting mechanism, pivoted crimping jaws, an endwise movable slide on which the jaws are carried, a support relatively to which the slide and jaws can be moved about an axis extending lengthwise 50 of the last, an operating handle fulcrumed on the support, pivotally connected to the slide and connected at a point more remote from its fulcrum with the jaws for closing them while they are advanced with the slide. 110
- 55 70. In an end lasting mechanism, pivoted crimping jaws, an endwise movable slide on which the jaws are carried, a support for the slide, an operating lever fulcrumed on the support and pivotally connected with 60 the slide for advancing it and the crimping jaws over a last, and links extending from the jaws to the lever at a point more remote from its fulcrum than is the pivotal connection of the lever with the slide whereby the 115
- jaws are closed together as they are advanced. 75
71. In a machine of the class described, the combination with a pair of crimping jaws, of a crimping plate, means for securing the crimping plate to the jaws, said plate having a slot extending from the securing means to the edge of the plate, whereby the plate may be withdrawn without removing the securing means. 80
72. In a machine of the class described, the combination with a pair of crimping jaws, a hollow stud on which the jaws are mounted and a crimping plate having a slot for the purpose described, of a screw bolt arranged to pass through the said slot and the hollow stud for holding the plate in position, substantially as described. 85
73. In a machine of the class described, the combination with a carriage, of a slide mounted thereon and crimping jaws supported by the slide, of means for vertically adjusting the slide and jaws about a center located substantially at the edge of the crimping jaws. 90
74. In a machine of the class described, the combination with lasting means comprising crimping plates and means for actuating them to do their work, a sliding support for the lasting means, a carriage or base on which the support is movable for 95 angular adjustment of the lasting means, and an arc-shaped tongue and groove connection between the support and the base having its center of movement substantially in the plane of action of the lasting means. 100
75. In a machine of the class described, the combination with lasting means comprising crimping plates and means for actuating them to do their work, a sliding support for the lasting means, a carriage or base on which the support is movable for angular adjustment of the lasting means, a connection from the support to the base, beveled gear teeth on said connection, a beveled pinion meshing with said teeth, and a shaft having a hand wheel for actuating said pinion to effect adjustment of the slide and the lasting means thereon. 105
76. In a machine of the class described, the combination with lasting means comprising crimping plates and means for actuating them to do their work, a sliding support for the lasting means, a carriage or base on which the support is movable for angular adjustment of the lasting means about a transverse axis located substantially in the plane of action of the crimping plates, and a connection between the crimping plates and said sliding support arranged to permit the plates to be adjusted about an axis extending lengthwise of the last and located substantially in the plane of action 120 of the crimping plates. 125

77. A lasting machine, having in combination, end wipers, an end side-lasting device, separate positioning means for said wipers and device, a support 170 for said 5 lasting device, and means, 160, 166, 170, thereafter to move said device in substantially a right line relatively to the last. 65
78. A lasting machine, having in combination, movable end wipers, an end side-lasting device, positioning means 56 therefor, means for moving said device relatively to the last, and means 144 permitting bodily movement of said device in another direction irrespective of said wiper movement 10 during said first mentioned movement. 75
79. A lasting machine, having in combination, a support, a wiper carrier mounted to move about an axis passing through the jacked shoe when the latter is in position to 15 be lasted, and an intermediate carrier supporting the wiper carrier and arranged to have movement about an axis passing through said jacked shoe at an angle to the axis of the wiper carrier movement. 80
80. A lasting machine, having in combination, the carriage base 180, the wipers, the wiper carrier 212 arranged to turn about an axis extending longitudinally of the shoe in the plane of action of the wipers, and the 25 intermediate wiper carrier 190 mounted for movement about an axis extending transversely of the shoe and located substantially at the front end of the shoe bottom. 90
81. A lasting machine, having in combination, a toe band 16, longitudinally sliding end supports 98 for said band, levers 80 connected with the free ends of said supports, an equalizing rod 90 connecting the levers, and a connection 14, 84 between the fulcra 30 of said levers. 95
82. A lasting machine having, in combination, an end embracing band, levers supporting at one end said band by its ends, and means including an actuating bar arranged 45 transversely of the shoe to spread the ends of the levers that are remote from said band and thereby force the two ends of the band together to clasp the upper about the end portion of the last. 100
83. A lasting machine having, in combination, an end embracing band, levers supporting at one end said band by its ends, and means to spread the ends of the levers remote from the band to force the two ends 50 of the band together and clasp the upper about the end portion of the last, said means including an actuator arranged transversely of the shoe and movable with the adjacent ends of the levers to equalize band closing 55 pressure at the two sides of the shoe. 105
84. A lasting machine having, in combination, an end embracing band, levers supporting at one end said band by its ends, and means to spread the ends of the levers 60 remote from the band to force the two ends 65 of the band together and clasp the upper about the end of the last, said means being arranged for bodily movement transversely of the shoe with the adjacent ends of the levers to equalize band closing pressure at 70 the two sides of the shoe when operating upon crooked lasts. 75
85. A lasting machine having, in combination, an end embracing band, levers supporting at one end said band by its ends, 75 means to spread the ends remote from the band to force the two ends of the band together to clasp the upper about the end portion of the last, and means for effecting adjustment of the spreader and the adjacent 80 ends of the levers transversely of and into non-symmetrical relation to the longitudinal median line of the machine. 85
86. In a lasting machine having a jack and a rotatable head carrying two lasting 90 mechanisms to be used alternately, said jack and head being relatively movable into different planes substantially parallel with the bottom of a last carried by the jack for turning without interference, and an automatically 95 acting locking device arranged to prevent turning movement of the head when said parts are in interfering planes and to permit turning movements when the jack and head are in non-interfering planes. 95
87. In a lasting machine having a jack and a rotatable head carrying two lasting 100 mechanisms to be used alternately, said jack and head being relatively movable into different planes substantially parallel with the bottom of a last carried by the jack for turning without interference, a treadle and connections for effecting said movements, and an automatically acting locking device controlled through said treadle and connections 105 and arranged to prevent turning movements of the head when said parts are in interfering planes and to permit turning movements when the jack and head are in non-interfering planes. 110
88. In a lasting machine, a jack, a rotatable head carrying two lasting mechanisms to be used alternately, one of said parts being movable relatively to the other into different planes to permit turning of the head 115 without interference, a treadle and connections for effecting said movements, and a locking device which is automatically rendered operative to prevent turning movements of the head when the jack and head 120 are in interfering planes and which is rendered inoperative to permit turning movements of the head when said parts are in non-interfering planes. 120
89. A lasting machine, comprising the 125 combination of lasting means shaped to embrace the end portion of a shoe and a supporting mechanism therefor, including a

block having a segmental lower bearing face, a carriage for said block having a correspondingly curved seat located entirely below the lasting means and engaging the face 5 of the block, and means for angularly adjusting the block upon said seat about an axis extending longitudinally of the last.

In testimony whereof I have signed my name to this specification in the presence of two subscribing witnesses.

ARTHUR ERNEST JERRAM.

Witnesses:

JOHN RICHARD LAW,
GRACE HOLMES.

Copies of this patent may be obtained for five cents each, by addressing the "Commissioner of Patents, Washington, D. C."

It is hereby certified that in Letters Patent No. 1,022,420, granted April 9, 1912, upon the application of Arthur Ernest Jerram, of Leicester, England, for an improvement in "Lasting-Machines," errors appear in the printed specification requiring correction as follows: Page 4, line 50, for the reference numeral "102" read *120*; page 8, line 58, for the word "comprising" read *comprised*; and that the said Letters Patent should be read with these corrections therein that the same may conform to the record of the case in the Patent Office.

Signed and sealed this 14th day of May, A. D., 1912.

[SEAL.]

C. C. BILLINGS,
Acting Commissioner of Patents.
